(57) **CLAIM**

The ornamental design for a drill bit strap device, as shown and described.

DESCRIPTION

FIG. 1 is a perspective view of the drill bit strap device of the present invention;

FIG. 2 is a front view of the drill bit strap device of the present invention;

FIG. 3 is a right side view of the drill bit strap device of the present invention;

FIG. 4 is a rear view of the drill bit strap device of the present invention;

FIG. 5 is a left side view of the drill bit strap device of the present invention;

FIG. 6 is a top view of the drill bit strap device of the present invention; and,

FIG. 7 is a bottom view of the drill bit strap device of the present invention.

1 Claim, 6 Drawing Sheets
